UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

TRANSMISSION OF PICTURES.

Application filed January 23, 1928. Serial No. 248,731.

My invention relates to the transmission of pictures, and has for its principal object the provision of an improved picture receiving apparatus which may be readily operated and controlled by those inexperienced in the use of such apparatus.

Various types of picture transmitting systems have been provided in the past. Many of these systems include a transmitting apparatus for scanning the elemental portions of the picture and producing electrical impulses which are proportional to the intensity or color of the light emitted by the successive elemental portions, and a receiving apparatus for converting these electrical impulses into light which may be applied to a sensitive film or other receiving element. In order to prevent distortion of the picture, it is essential that means be provided for establishing synchronism between the moving parts of the transmitting and receiving apparatus. Thus when a sensitive film is employed to receive the picture, it is necessary that the movement of the picture be duplicated by that of the film. In accordance with my invention, these results are produced by an improved apparatus and method of operation whereby the picture receiving or recording element is moved in one direction at a predetermined speed and is readily put into motion in another direction.

My invention will be better understood from the following description when considered in connection with the accompanying drawing and its scope will be pointed out in the appended claims.

Referring to the drawing, Fig. 1 is a perspective view of a picture receiving apparatus constructed in accordance with my invention, and Figs. 2 to 4 illustrate various details of the apparatus of Fig. 1.

This apparatus comprises a rotatable drum 1 which supports the receiving film and is coupled to a driving motor through gears 3 and 4, hollow shafts 5 and 6, and rods 7 and 8. Extending through the hollow shafts 5 and 6 is a shaft 9 provided at its end with a brake pulley 10 and threaded at its central portion to engage a pair of nuts 11 and 12 which cooperate with the rods 7 and 8 and the shaft 9 to move the drum 1 along the axis of the shaft in a direction dependent on the direction of the rotation of the motor 2. A brake shoe controlled by a handle 14 is arranged to cooperate with the brake pulley 10.

With this construction, the friction between the shaft 9 and the hollow shafts 5 and 6 causes the drum 1 and the shaft 9 to be driven at the same speed when the brake shoe 13 and brake pulley 10 are disengaged from one another. When the brake pulley and shoe are in engagement with one another, however, rotation of the shaft 9 is prevented and the drum 1 is moved along the axis of the shaft 9 by the nuts 11 and 12 which are threaded on this shaft. Movement of the drum along the axis of its rotation is thus readily started and stopped while the drum is rotating.

The drum 1 is mounted within a casing 15 provided with a hinged top and side cover 16 and is arranged to move past the eye piece of a telescope 17 which extends into the casing 15 and transmits light from a suitable source 18 to the recording element mounted on the drum 1. The light produced by the source 18 is modulated by the electrical impulses transmitted to it from an antenna 19 through an amplifying apparatus 20 of any suitable type. In the operation of the apparatus described herein, a neon glow lamp has been found particularly suitable for the purpose of converting the received electrical impulses into light impulses but it will of course be understood that any other suitable source of light may be utilized for this purpose.

Various means may be utilized for determining when synchronism is established between the rotation of the drum 1 and the member on which the picture to be transmitted is mounted. One suitable means for accomplishing this result is a contact disk 21 which is mounted on the hollow shaft 5, is provided with an insulation segment 22 and is arranged to cooperate with a pair of brushes 23 connected to the amplifier 20 through a switch and a telephone 25 or other suitable indicating device.

Assuming the picture transmitting apparatus to be provided with means for producing and transmitting synchronizing impulses depending on the rotational speed of the member on which the picture is mounted, these synchronizing impulses will produce an indication at the device 25 at all times except when they occur during the period of contact between the insulation segment 22 and the brushes 23. When the speed of the motor 2 is so adjusted that this period of contact always

coincides with the synchronizing impulses, no indication is produced at the device 25 and the picture transmitting and receiving drums are rotating at the same speed. Sync 5 chromism between the axial movements of the transmitting and receiving drums of course results from the similarity in the construction of the transmitting and receiving apparatus.

10 What I claim as new and desire to secure by Letters Patent of the United States, is:

1. A picture receiving apparatus including a rotatable member, a threaded member mechanically coupled to said rotatable member 15 through frictional contact between said members, and means arranged to cooperate with said threaded member for moving said rotatable member along its axis of rotation when said rotatable and threaded members 20 are moved with respect to one another.

2. A picture receiving apparatus including a pair of rotatable members mechanically coupled together through frictional contact therebetween, means for producing relative 25 movement between said members, and means

responsive to said relative movement for causing one of said members to be moved along the rotational axis of said members.

3. A picture receiving apparatus including a movable member, a member arranged to be driven by said movable member through frictional contact between said movable and driven members, means for producing relative movement between said movable and driven members, and means responsive to said 35 relative motion for causing one of said members to be moved in a direction transverse to the movement of the other of said members.

4. A picture receiving apparatus including a rotatable member, a member arranged to be driven through frictional contact between said members, a brake for causing relative movement between said rotatable and movable members, and means responsive to said relative movement for causing said rotatable 40 member to be moved along its axis of rotation.

In witness whereof, I have hereunto set my hand this 21st day of January, 1928.

ERNST F. W. ALEXANDERSON.
